LABEL SEWING MACHINE

Emil Prazak, deceased, late of Elizabeth, N. J.,
by Emil Prazak, Jr., Elizabeth, N. J., administrator

Application July 2, 1938, Serial No. 217,121

9 Claims. (Cl. 112—104)

This invention relates, generally, to improvements in sewing machines, and the invention has reference, more particularly, to a novel improved sewing machine especially adapted for attaching labels and the like to various kinds of articles by a stitching operation.

The invention has for an object to provide a novel means for supporting and holding an article and a label to be attached thereto, and thereupon automatically moving or feeding the same subject to the operation of a sewing or stitching mechanism so that the label is securely sewn to the article in a desired position thereon; and to this end the machine includes novel means for imparting both rotative and axial step by step movements to the work and label support relative to the sewing mechanism of the machine, whereby the label attaching stitches are made.

The invention has for another object to provide means for automatically stopping the machine upon completion of a label attaching operation, including means under control of the operator for starting the machine at will to initiate the label attaching operation.

Still another object of the invention is to provide a label sewing machine comprising relatively few and simple parts and inexpensive to manufacture, rugged in construction and efficient in operation to a high degree.

Other objects of this invention, not at this time more particularly enumerated, will be understood from the following detailed description of the same.

An illustrative embodiment of the novel sewing machine according to this invention is shown in the accompanying drawings, in which:

Fig. 1 is a side elevation of the label sewing machine; Fig. 2 is a top or plan view of the same with portions broken away; Fig. 3 is a fragmentary side elevation, showing the work support with the work and label holding means thereof in open condition; Fig. 4 is a rear end elevation of the machine, with portions broken away to show interiorly disposed parts of the means for effecting operative movements of the work support; Fig. 5 is a fragmentary vertical longitudinal section, taken on line 5—5 in Fig. 4; Fig. 6 is a detail view showing the cam means which effects and times the rotative movements of the work support; Fig. 7 is a detail view showing the cam means which effects and times the axial movements of the work support; Fig. 8 is a fragmentary sectional view, taken on line 8—8 in Fig. 4, showing portions of the automatic stop means of the machine; Fig. 9 is a fragmentary horizontal

sectional view, taken on line 9—9 in Fig. 4, showing portions of the detent devices of the stop means, as released; and Fig. 10 is a similar view, showing the detent means in holding relation to the stop means.

Fig. 11 is a rear face view of a portion of a necktie bearing a label as attached thereto by the operation of the sewing machine of this invention.

Similar characters of reference are employed in the hereinabove described views, to indicate corresponding parts.

In said drawings, the reference character 1 indicates the main body of the sewing machine frame or base from the top of which extends the arm 2 through which extends the head shaft 3 for operating any well known type of mechanism for actuating the vertically reciprocable needle bar 4 and the sewing needle 5 carried by the latter.

Extending from said frame or base body 1 is a tubular bearing arm 6 by which the work support of the machine is movably supported. Said work support comprises a hollow or tubular mandrel 7 having a tapered or conical free end portion, preferably in the form of a removable end cap 8. The rearward end of said mandrel 7 extends within the interior of said frame or base body 1, and is movably mounted on a tubular bearing hub 9 which is suitably secured to said frame or base body. Said mandrel 7 is aligned beneath the machine arm 2 in spaced relation to the sewing needle mechanism. Formed in the top wall portion of the mandrel 7 is a transverse slot or needleway 10 which terminates at its respective ends in rearwardly directed longitudinal extension slots or needleways 11. Arranged within the interior of said mandrel 7, beneath the slots or needleways, is auxiliary sewing mechanism to cooperate with the reciprocating sewing needle 5 in the stitch-forming operations of the machine. For the purposes of illustration, said auxiliary sewing mechanism is shown as of the well-known reciprocating shuttle type 12, although it will be obvious that other types may be employed, such as the equally well-known rotary or oscillating hook type. As shown, the means for actuating the shuttle 12, in properly timed relation to the reciprocatory movements of the sewing needle 5, comprises a bell-crank lever 13 which is pivotally supported between the ends of laterally spaced bracket arms 14 projecting rearwardly from the butt of the machine arm 2. To the free end of the vertical arm 15 of said bell-crank lever is pivotally connected the rearward end of a reciprocable link 16 which extends for-

wardly through the interior of the mandrel 7, and with the free end portion of which is connected said shuttle 12, whereby the operative movement is transmitted to the latter. Affixed on the rearward end of the head shaft 3 is a crank wheel 17 which is operatively connected with the horizontal arm 18 of said bell-crank lever by a connecting rod member 19.

The mandrel 7 is provided with means for 10 clamping the work and a superposed label thereto subject to the machine stitching operations. An illustrative form of clamping means suitable for the purpose comprises a split collar 20, the sections of which are suitably secured together to 15 and around the mandrel 7. Pivots connected with the upper section of said collar 20, by a cross-pin 21 carried by the latter, is a carrier arm 22 to the free end of which is suitably affixed a label frame 23. Said label frame is of open 20 rectangular shape and transversely arcuate in form to conform to the circumferential curvature of the mandrel 7, and the same is so dimensioned as to extend exteriorly around the slots or needleways 10-11 of the latter. A second carrier arm 25 24 is provided, the same having a bifurcated rear end 25, the arms 26 of which straddle said upper section of the collar 20, being pivotally mounted upon the ends of the cross-pin 21 carried by the latter. The arms 26 terminate in downwardly 30 and rearwardly inclined lever extensions 27. Pivots connected, by clevis portions 28, with the free ends of said lever extensions 27 are rods 29, the free end portions of which extend slidably through knuckles 30 rotatably mounted in 35 connection with the lower section of said collar 20. Compression springs 31 are disposed about said slide rods 29 between their clevis portions 28 and said knuckles 30. Affixed to the free end of said second carrier arm 24, by a downwardly off 40 setting tail-piece 32 is a label and work clamp plate 33 of transversely arcuate shape adapted to conform to the circumferential curvature of the mandrel 7. When in clamping position, said clamp plate 33 will enter downwardly within the 45 label frame 23 to register within the area defined by the inner margins of the slots or needleways 10-11, so as not to obstruct the passage of the sewing needle 5 through and along the latter during the sewing operations of the machine. If 50 desired, the second carrier arm 24 may have suitably connected therewith a transverse finger piece 34 to facilitate manipulation of the same.

Provided in connection with the machine arm 2 is a laterally projecting bearing arm 35 which 55 overhangs the frame or base body 1, and secured to said frame or base body 1 so as to be aligned with said bearing arm 35, in outwardly offset relation thereto, is a bearing bracket 36. Journaled in said bearing arm 35 and bearing bracket 60 36 is a transverse drive shaft 37. Said drive shaft 37 is adapted to drive the head shaft 3 through the agency of intermeshing gears 38 and 39 respectively affixed to these shafts. Affixed upon the outer end portion of said drive shaft 37 is a 65 drive pulley 40, and also mounted loosely on said drive shaft 37, outwardly of said drive pulley 40 is a loose or idler pulley 41. A drive belt 42 cooperates with said pulleys, and is adapted to be driven from any suitable power source.

70 Journaled in bearing portions 43, provided in connection with said frame or base body 1, is a transverse counter or jack shaft 44 which is positioned in downwardly and rearwardly offset relation to said drive shaft 37. Fixed on the forward end of said jack shaft 44 is a cam wheel 45 for

controlling and timing the rotative movements of said mandrel 7. Fixed on the rearward end of said jack shaft is a cam wheel 46 for controlling and timing the longitudinal or axial movements of said mandrel 7.

The means for driving said jack shaft 44 and the cam wheels 45 and 46 thereof, comprises an oscillator member 47 which is pivotally mounted on said jack shaft 44 as a fulcrum. Said drive shaft 37 is provided with an eccentric 48 which is 10 connected with said oscillator member 47 by a connecting rod 49. Fixed on said jack shaft 44, adjacent to said oscillator member 47, is a ratchet wheel 50. Pivotally mounted on said oscillator member 47 is a spring-pressed pawl 51 adapted 15 to cooperate with said ratchet wheel 50. The rotary movement of the drive shaft 37 is transmitted through the eccentric 48 and connecting rod 49 to the oscillator member 47, thereby producing operative oscillation of the latter so as to cause the pawl 51 to progressively rotate the ratchet wheel 50, and thus also driving the jack shaft 44 and said cam wheels.

The means for transmitting rotary motion to the mandrel 7 comprises a vertically movable rack 52 slidably supported in slideway members 53 within the interior of the frame or base body 1 adjacent to the forward wall thereof. Mounted within the interior of said frame or base body 1, to extend adjacent to and across said rack 52, is a rock shaft 54 upon which is fixed a gear 55 to operatively mesh with said rack. Also fixed on said rock-shaft 54 is a quadrant gear 56 which operatively meshes with a gear 57 affixed to the rearward end portion of said mandrel 7. Affixed to said rack 52 is a laterally projecting stud 58, which projects outwardly through a slot 59 in the adjacent wall of said frame or base body 1 and toward said cam wheel 45, and mounted on the end of said stud is an anti-friction roller 60 which engages in the race of said cam wheel 45. The race of the cam wheel 45 is formed to provide a rack lowering cam section 61 and a rack raising cam section 62 with intermediate neutral race sections 63 and 64. The rack lowering cam section 61 operates to slide downwardly the rack 52, thus transmitting an upswinging movement to the quadrant gear 56 which operates, through the gear 57, to impart clockwise rotary movement to the mandrel 7 (as viewed in Fig. 4). The cam sections 61 and 62 are of the sinuous form shown (see Fig. 6), whereby the produced rotary movement of the mandrel 7 is intermittent or step by step in character and timed relative to the reciprocations of the sewing needle 5, so that a slight hesitation or dwell of the mandrel, and the work borne thereby, occurs as said needle passes into and withdraws from the work, while, at the same time, the step by step progression is utilized to feed or move the work relative to the path of movement of the needle 5, to thus determine the length of the stitches formed by the sewing operation of the sewing mechanism of which said needle 5 is a part.

The means for transmitting longitudinal or axial motion to the mandrel 7 comprises a lever 65 pivoted by its upper end upon a pivot stud 66 carried by an ear or lug 67 springing from the machine arm 2. Said lever 65 extends downwardly across the face of the cam wheel 46, and carried by its lower end is an inwardly projecting anti-friction roller stud 68 to operatively engage in the annular channel 69 of a thrust collar 70 which is fixed upon the rearward end portion of said mandrel 7. Mounted on the outer 75

side of said lever 65, intermediate the ends thereof, is an anti-friction roller stud 71 which engages in the race of said cam wheel 46. The race of said cam wheel 46 is formed to provide 5 a mandrel advancing and retracting cam sections 72 and 73 with intermediate neutral race sections 74 and 75. The cam sections 72 and 73 are of the sinuous form shown (see Fig. 7), whereby the produced longitudinal or axial movements, in both directions, is intermittent or step 10 by step in character and timed relative to the reciprocations of the sewing needle 5, so that a slight hesitation or dwell of the mandrel, and the work borne thereby, occurs as said needle 15 passes into and withdraws from the work, while, at the same time, the step by step progression is utilized to feed or move the work relative to the path of movement of the needle 5, to thus determine the length of the stitches formed by the 20 sewing operation of the sewing mechanism of which said needle 5 is a part.

The novel sewing machine is provided with means for manually starting its operation and thereafter automatically stopping such operation when the sewing on of a label or the like to a given article is completed. This means comprises a stop dog 76 pivoted at its lower end by a fulcrum knuckle 77 which projects from a bracket plate 78 mounted exteriorly on the frame 25 or base body 1. The free end of said stop dog 76 extends upwardly behind the drive pulley 40, and is yieldably urged toward the latter by spring means 79 disposed intermediate the stop dog 76 and said bracket plate 78. Mounted in the free 30 end portion of said stop dog 76 is a spring projected stop bolt 80. Affixed on the rearward face of said drive pulley 40 is a stop collar 81 having an eccentric periphery terminating at its high side in a radial stop shoulder 82, contiguous to the bottom of which is a transverse check groove 35 83 (see Fig. 8). Affixed to the upper free end of said stop dog 76 is a belt shifter 84, through the loop of which passes a run of the drive belt 42. Pivotally fulcrumed between bracket ears 40 85, which project outwardly from said bracket plate 78 in straddling relation to said stop dog 76, is a bell-crank lever, the inner vertical arm 86 of which extends downwardly along the outer face of the stop dog 76, while the horizontal arm 45 87 of which projects outwardly and may be manipulated by hand, or, if desired, may be connected by a pull-wire 88 with a foot pedal (not shown) so as to be actuatable by the machine operator's foot. Cooperative with said stop dog 50 76 is a detent member 89 which is pivotally mounted by its hub 90 in connection with said bracket plate 78 so as to swing in horizontal plane toward and from a side of said stop dog. Said detent member 89 is provided with a latch nose 91 to engage a chamfered latching lip 92 with which said stop dog is provided. Said detent member 89 is yieldably urged toward said stop dog by spring means 93. Affixed to the hub 55 90 of said detent member 89 is trip arm 94 having an upstanding trip nose 95 at its free end portion. Means is provided for automatically releasing said detent member 89 upon completion of a label sewing operation, said means operating in timed relation to the means producing 60 the operative rotary and axial movements of the mandrel 7. Said releasing means comprises a worm-wheel 96, rotatably mounted on a bracket bearing 97 carried by said bracket plate 78 so as to turn in horizontal plane. Said worm-wheel 65 is driven by a worm gear 98 which is fixed on the 70 75

drive shaft 37. Carried by said worm wheel 96, in dependent relation to the underside thereof, is a trip stud 99, which is adapted at proper times to engage said trip nosing 95 of the detent trip arm 94.

In the use of the machine, the same being in stopped condition, the operator raises the clamp plate 33 and the label frame 23 to open position shown in Fig. 3, and, thereupon slides the work to be labeled over the free end of the mandrel 7 10 and beneath the raised clamp plate and label frame. Illustrative of the work, the same may be a necktie T, across the lapped back folds of which it is desired to sew the label L. In such case, the necktie T is slid onto the mandrel 7 15 with its rear face uppermost, and so that the mandrel passes between the front and back thereof in underlying relation to the latter. When the necktie T is in position beneath the raised sewing needle 5, the label frame 23 is lowered, 20 and thereupon the label T is laid over the rear face of the necktie within the label frame 23, by which the margins of the label are disposed in register over the needleways 10—11 of said mandrel, whereupon the clamp plate 33 is lowered 25 to clamp and firmly hold the tie and label gripped against the mandrel 7.

With the work positioned as described, the operator starts the machine. This is done by pulling down the horizontal arm 87 of the bell-crank, thus swinging inward the vertical arm 86 thereof against the stop dog 76, whereby the latter is swung rearwardly to withdraw the stop-bolt 80 from the path of the stop shoulder 82, while at the same time moving inwardly the belt shifter 84, so that the continuously moving power belt 42 is shifted from the loose or idler pulley 41 onto the drive pulley 40. The stop dog is held in the described released or retracted position by the engagement of its latching lip 92 by the 30 latch nose 91 of the detent member 89.

As the drive belt 42 engages the drive pulley 40 operation of the machine is inaugurated, the sewing needle 5 begins its vertical reciprocation and cooperation with the other elements of the 45 stitch forming mechanism, and simultaneously the movement of the cam wheels 45 and 46 begins. It is preferable, although not essential, that the stitching operations start from the middle of the transverse needleway 10 proceeding thence to one longitudinal needleway 11. In such case, the starting point of an operative cycle of movement of the cam wheel 45 is located midway of the ends of one of the rack actuating cam sections of its race, as e. g. the 50 middle of the rack lowering cam section 61 (see Fig. 6). Starting from this point, the initial movement of the cam wheel causes a downward movement of the rack 52, and through the transmission mechanism actuated thereby, produces 55 a step by step rotative movement of the mandrel 7, and work clamped thereto, in the direction of the arrow x in Fig. 2. Such step by step movement is produced in timed relation to the reciprocations of the sewing needle 5, and consequently a series of stitches along the longitudinal margin of the label L is formed, until the end of the transverse needleway 10 is reached, by which time the rack 52 is stopped at the limit of its downward movement and 60 there caused to dwell as its stud roller 60 enters and rides through the neutral cam race section 63. Immediately such rotative movement of the mandrel and work ends, the cam wheel 46, which 65 revolves in company with the cam wheel 45, has 70 75

brought one of its race cam sections, as 72, into engagement with the stud roller 71 of the lever 65, whereby, as said cam section moves relative to said stud roller, said lever 65 is caused to swing forward and back, thus axially moving the mandrel 1, and work clamped thereto, step by step forward and back in the directions of the arrow *a* in Fig. 2 and consequently stitching along an end margin of the label L is formed, until the sewing needle 5 is returned to the juncture of the operative needleway 11 and said transverse needleway 10, by which time the lever 65 is stopped in initial position and there caused to dwell as its stud roller enters and rides through the neutral cam race section 74 of the cam wheel 46. Immediately such axial movement of the mandrel ceases, the rack raising cam section 62 of cam wheel 45 becomes operative, thus causing a rotative movement of the mandrel and work in the direction of the arrow *y* in Fig. 2, with stitch forming effect, until the opposite end of the transverse needleway 10 is reached, by which time the rack 52 is stopped at the limit of its upward movement and there caused to dwell as its stud roller 60 enters and rides through the neutral cam race section 64. Immediately such rotative movement of the mandrel and work ends, the race cam section 73 of cam wheel 46 becomes operative, thus causing a second axial movement of the mandrel and work in the directions of the arrow *b* in Fig. 2, with stitch forming effect along the second needleway 11, and until the juncture of the latter with the transverse needleway 10 is again aligned with the sewing needle 5, whereupon the neutral race section 75 of cam wheel 46 becomes effective, and the cam race section 61 of cam wheel 45 again becomes effective to rotate the mandrel and work back to initial starting position.

It will be observed that the cam wheels 45 and 46 have their operative and neutral race sections in alternated effective relation, thus timing the operations of the sewing mechanism to stitch along one longitudinal margin and along the end margins of the label L. As shown and above described, the arrangement and operation is such that a double line of stitching is produced. It will be obvious, that variations in the relative arrangements of the operative and neutral race sections of the cooperating cam wheels can be made, so as to begin and end the stitching operations at any desired portion of the label margin or so as to produce either single, double or multiple rows of stitching, as may in any given case be desired.

The operation of the means for automatically stopping the machine upon completion of the stitching operations is as follows:

60 When the stop dog 76 is swung back as described to shift the drive belt 42 onto the drive pulley 40, the detent member 89 will engage and hold said stop dog 76 in such out of service position. As the machine proceeds to perform its 65 cycle of operation, the worm gear 98 will cause the worm wheel 96 to revolve in such manner and timed relation to the machine operation that, upon completion of the stitching, the trip stud 93 carried by said worm wheel 96 will be brought 70 into passing engagement with the trip nose 95 of trip arm 94. Such engagement will swing said trip arm 94 so as to transmit an outward swinging movement to said detent member 89 (see Fig. 9) thus releasing its restraint upon the 75 stop dog 76. When the stop dog 76 is thus re-

leased, the spring 79 will swing the same outward, to carry its stop bolt 80 into the path of movement of said stop shoulder 82 of the stop collar 81. Due to the eccentric periphery of the stop collar 81, the stop bolt 80 will be depressed so that as the check groove 83 comes into alignment therewith, the end of said stop bolt 80 will be projected into said check groove 83, while at the same time the stop shoulder 82 will be stopped against the side of said stop bolt 80. Such operation assures a full stop of the drive pulley 40 without risk of either back-lash or carry over thereof under momentum, and consequently also assuring the full stopping of the sewing mechanism and work support in an accurate normal initial position. The outward movement of the stop dog 76 to operative position as described, also moves outwardly the belt shifter 84, thus shifting the continuously running drive belt 42 onto the loose or idler pulley 41.

When the machine is thus automatically stopped upon completion of a given label sewing operation, the work and label clamp 33 may be released and the label frame 23 raised so that the tie T may be removed from the mandrel 1, and another tie T and label applied to the latter ready for a repetition of the above described operations.

As many changes could be made in the above described constructions and many apparently widely different embodiments of this invention could be made without departing from the scope thereof, as defined by the following claims, it is intended that all matter contained in the above description or shown in the accompanying drawings shall be interpreted as illustrative and not in a limiting sense.

What is claimed is:

1. In combination, a hollow cylindrical work support having a slotted needleway in the wall thereof, a sewing mechanism including a vertically reciprocable sewing needle opposed to said work support for movement in and out of said needleway, stitch forming means within the hollow interior of said work support for cooperation with said sewing needle, and means to automatically impart rotative and axial movements to said work support to shift its needleway relative to the reciprocating sewing needle.

2. In combination, a hollow cylindrical work support having a slotted needleway in the wall thereof, means to releasably secure the work to the exterior of said support in overlying relation to said needleway, a sewing mechanism including a vertically reciprocable sewing needle opposed to said work support for movement in and out of said needleway, stitch forming means within the hollow interior of said work support for cooperation with said sewing needle, and means to automatically impart rotative and axial movements to said work support to shift its needleway and the work step by step in successively changing directions relative to the reciprocating sewing needle.

3. In a sewing machine, a hollow mandrel mounted subject to both rotative and axial shifting movements, said mandrel having a needleway opening through its wall and including a transverse portion and longitudinal portions extending respectively from the ends thereof, means to releasably secure work to said mandrel in overlying relation to said needleway, sewing mechanism including a vertically reciprocable sewing needle opposed to said mandrel needleway and stitch forming means within said mandrel for

cooperation with said sewing needle, and relatively timed mandrel actuating means for producing both longitudinal and rotative movements of said mandrel to shift the work together with the longitudinal and transverse portions of the needleway across the path of needle reciprocation to form runs of stitching through the work.

4. In a sewing machine, a hollow mandrel mounted subject to both rotative and axial shifting movements, said mandrel having a needleway opening through its wall and including a transverse portion and longitudinal portions extending respectively from the ends thereof, means to releasably secure work to said mandrel in overlying relation to said needleway, sewing mechanism including a vertically reciprocable sewing needle opposed to said mandrel needleway and stitch forming means within said mandrel for cooperation with said sewing needle, relatively timed mandrel actuating means for producing both longitudinal and rotative movements of said mandrel to shift the work together with the longitudinal and transverse portions of the needleway across the path of needle reciprocation to 25 form runs of stitching through the work, a driven transmission mechanism for operating both said sewing mechanism and said mandrel actuating means.

5. In a label sewing machine, a hollow mandrel mounted subject to both rotative and axial shifting movements, said mandrel having a needleway opening through its wall and including a transverse portion and longitudinal portions extending from the ends thereof, a label frame to 30 overlie work supported on said mandrel and adapted to receive and hold a label in register with said mandrel needleway, means for clamping the work and superposed label to said mandrel, a sewing mechanism including a vertically reciprocable sewing needle opposed to said mandrel needleway and stitch forming means within said mandrel for cooperation with said sewing needle, and relatively timed mandrel actuating means for producing both longitudinal and rotative movements of said mandrel to shift the work and superposed label together with the longitudinal and transverse portions of the needleway across the path of needle reciprocation to form stitching for attaching the label to the work.

6. In a sewing machine as defined in claim 3 wherein the mandrel actuating means comprises, a rotative shift cam wheel and an axial shift cam wheel, a rack operated by said rotative shift cam wheel, transmission gearing between said rack and mandrel, a pivoted lever operated by said axial shift cam wheel, means to engage said lever in operative relation to said mandrel, said cam wheels having their effective cam sections 45 relatively disposed to time the rotative and axial shift movements imparted to said mandrel in

desired successive order, and means for driving said cam wheels.

7. In a label sewing machine, a hollow mandrel mounted subject to both rotative and axial shifting movements, said mandrel having a needleway opening through its wall and including a transverse portion and longitudinal portions, a label frame to 10 overlie work supported on said mandrel and adapted to receive and hold a label in register with said mandrel needleway, means for clamping the work and superposed label to said mandrel, a sewing mechanism including a vertically reciprocable sewing needle opposed to said mandrel needleway and stitch forming means within 15 said mandrel for cooperation with said sewing needle, mandrel actuating means including a rotative shift cam wheel and an axial shift cam wheel, a rack operated by said rotative shift cam wheel, transmission gearing between said rack and mandrel, a pivoted lever operated by said axial shift cam wheel, means to engage said lever in operative relation to said mandrel, said cam wheels having their effective cam sections relatively disposed to time the rotative and axial shift movements imparted to said mandrel in desired 20 successive order, and a driven transmission mechanism for operating both said sewing mechanism and said cam wheels.

8. In a label machine, a hollow work support 25 provided with a needleway, a pivotally mounted label frame carried by said work support to overlie work supported thereon and adapted to receive and hold a label in register with said needleway and with a predetermined line of stitching, spring biased means also carried by said work support for clamping the work and superimposed label thereon, and a sewing mechanism including a vertically reciprocable sewing needle opposed to said needleway, and stitch forming means within said work support for 30 operation with said needle.

9. In a label sewing machine, the combination with a stitch-forming mechanism including a vertically reciprocable sewing needle, an axially and rotatively reciprocable hollow work supporting mandrel disposed beneath said sewing needle and within which a needle cooperating part of the stitch-forming mechanism is contained, means carried by said mandrel to clamp work thereto, means also carried by said mandrel to clamp a 35 label in superposed relation to the work, means to effect axial movements of said mandrel, and means to effect rotative movements of said mandrel, said latter respective means being operated in timed relation one to the other whereby the work with the superposed label is moved relative to the sewing needle in successively changing directions.
